HUMIDIFIER

James E. Myers, Whitefish Bay, Wis.

Application February 19, 1934, Serial No. 711,888
Renewed September 8, 1936

10 Claims. (Cl. 261—15)

The present invention relates in general to improvements in the art of air conditioning, and relates more specifically to improvements in the construction and operation of humidifying apparatus for controlling the moisture within a room or other enclosure.

Generally defined, an object of the invention is to provide an improved humidifier which is simple in construction and which is, moreover, highly efficient in operation.

Some of the more specific objects of the invention are as follows:

To provide effective humidifying apparatus which is devoid of noisy movable parts, and wherein the moisture carrying and distributing gas is propelled by natural draft alone.

To provide an improved air conditioner which is automatic in operation and which is adaptable to a wide range of uses.

0 To provide a compact, portable humidifying unit which may be readily transferred from place to place, and which may also be utilized as an article of furniture.

To provide a humidifier wherein the rapidity or the degree of humidification can be quickly varied as desired, and in which danger of escape of excess liquid is entirely eliminated.

To provide an air moistening device for rooms or other enclosures, which is of neat and pleasing appearance, and which may be manufactured and operated at minimum cost.

To provide improved liquid distribution structure for humidifying apparatus, which will automatically distribute particles of moisture across the path of a stream of heated gas in a manner which will insure rapid absorption of the liquid and uniform distribution of the moisture.

These and other objects and advantages will be apparent from the following detailed description.

A clear conception of the embodiments of the various features constituting the present improvement, and of the mode of constructing and of operating humidifiers built in accordance with the invention, may be had by referring to the drawing accompanying and forming a part of this specification, in which like reference characters designate the same or similar parts in the various views.

0 Fig. 1 is a vertical section thru an improved humidifier, showing the general internal arrangement of the parts;

Fig. 2 is a transverse horizontal section thru the improved humidifier, taken along the line 2—2 of Fig. 1;

Fig. 3 is a full front view of the improved humidifier, drawn to a somewhat smaller scale;

Fig. 4 is a vertical section thru the upper portion of the humidifier, taken along the line 4—4 of Fig. 1, directly to the rear of the front grille; 5

Fig. 5 is a diagram of the water and heat control mechanism for varying the degree of humidification.

While the invention has been shown and described herein as being specifically applied to a portable unit for rooms, it is to be understood that some of the novel features are more generally applicable to fixed or permanently installed humidifiers and air conditioners, and that it is not intended to limit the invention to the portability of the apparatus. 10

With reference to the drawing, the improved portable humidifier specifically shown therein by way of illustration comprises in general a main housing or casing 8 having therein a partition 9 forming an upwardly extending gas passage 10; one or more heaters 11 removably supported within the medial portion of the passage 10; means for causing liquid such as water to percolate across the passage 10 above the heaters 11 and preferably near the outlet 12 thereof; and means for varying both the quantity of liquid and the degree of heating. 20

The main casing 8 may be formed of wood or metal, suitably decorated or finished to present a pleasing appearance, and is provided with supporting legs 13 for spacing the lower portion of the casing from the floor, and with a top cover 14 for permitting convenient access to the interior 25 of the casing 8. The front of the casing 8 may be provided with a decorative grille 15 spanning the outlet 12 of the flue passage 10, and the lower interior of the main casing may also be provided with supporting bars 16 upon which the internal humidifying structure is removably mounted. The partition 9 which spans the interior of the casing 8 from side to side, is attached to side plates or frames 17 and is curved adjacent the outlet 12 for the dual purpose of changing the 30 direction of flow of the gas thru the passage 10 from vertical to horizontal, and of reflecting the heat rays from the heaters 11 so as to insure most effective distribution thereof thru-out the passage 10. 35

The heaters 11 which are illustrated as being of the electric cone type, are removably mounted in sockets 18 carried by a transverse supporting bar 19 secured to the side frames 17, one of which may be provided with a side opening 20 for per-

mitting access to the heating units when these supporting frames are lifted out of the main casing 8. The energizing switch 21 for the heaters 11 may be disposed near the upper side portion 5 of the casing 8 near the cover and is of such construction that either one or both heaters may be energized, depending upon the degree of heating desired. While electric heaters of a specific type have been shown, any other form of heating medium may be substituted. It is also to be noted 10 that these heaters are disposed within the passage 10 above the inlet 22 of the passage 10, and this inlet 22 is in open communication with the ambient atmosphere thru the spaces afforded by the 15 supporting legs 13 of the main casing 8.

The means for causing the liquid to percolate across the passage 10 near the outlet 12, is of 20 importance and should produce uniform and automatic distribution of the liquid in film-like form over the entire outlet. This liquid distributing means comprises a supply tank 23 carried by the upper ends of the side frames 17 directly beneath the cover 14; a drip catch or reservoir 24 disposed in front of the passage 10 near the 25 lower ends of the frames 17; and a screen 25 corrugated to provide a series of transverse liquid distributors resembling a louver spanning the outlet 12 directly in back of the casing grille 15. The supply tank 23 has a filling plug 26 and a 30 discharge valve 27 which is adapted to regulate the flow of liquid to a distributing header 28 disposed below the tank and above the distributing screen 25. The header 28 extends across the interior of the casing 8 and has a series of upper 35 liquid discharge openings within each of which a wick 29 is disposed, the inner ends of these wicks extending in close proximity to the header bottom and the outer ends thereof being disposed exteriorly of the header 28 and preferably hanging 40 alongside of the same so as to cause the escaping liquid to flow by capillary attraction and in uniform fine streams upon the upper portion of the screen 25. While this delivery of liquid from within the header 28 is effected primarily 45 by the head of liquid within the tank 23, the wicks 29 will tend to equalize the flow thru the several outlets and will also prevent clogging of these outlets. A guiding casing 30 is disposed near the header 28 and provides a housing for the wicks 50 29, and this casing serves to conduct the streams of liquid upon the upper distributor of the screen 25. Each of the superimposed substantially horizontal distributors is formed as a trough-like strip of screening having substantially V-shaped trans- 55 verse cross-section, and a porous strip or wick 31 of asbestos or the like also having substantially V-shaped transverse cross-section, disposed within the V-shaped screen trough. The liquid delivered into the upper trough-like distributor of 60 the screen 25 by the wicks 29, percolates thru the wick 31 and the perforated support therefor and gravitates along the intervening inclined screen portion to the next lower distributor, and so on, until the entire louver is saturated and is 65 retained in saturated condition, the degree of saturation and the rate of percolation however, depending upon the setting of the control valve 27. Any excess liquid reaching the lowermost end of the screen 25 will drip into and will accumulate 70 within the reservoir 24 which is provided with a valve controlled drain 32 as shown. The tank 23 may also be provided with a valve controlled drain pipe 33 communicating with the drain 32, and while the water would ordinarily be 75 used as a humidifying medium, other liquid such

as perfume, or a sterilizing liquid, or a medicinal fluid, may also be utilized.

The means for varying the quantity of liquid and the degree of heating so as to change the rate and extent of humidification may partake various forms, but as shown herein, this control means comprises the switch 21 and the regulating valve 27. As previously indicated, the switch 21 is operable to energize one or more of the heaters 11, and the valve 27 is operable to vary the quantity of liquid delivered from the tank 23 to the header 28. By connecting the levers for actuating these control elements as shown in the diagram, or by utilizing a common control lever in an obvious manner, the quantity of liquid thus delivered from the tank 23 to the distributing structure can obviously be varied in accordance with the degree of heating. If all of the heaters 11 are effective, maximum delivery of liquid will be effected, and the quantity of liquid will be reduced as the heaters are cut out. When all of the heaters are off, the liquid supply will also be shut off, thus enabling simultaneous control of the heat and liquid. The electric wiring may be confined in conduit as shown, and may be provided with an ordinary plug connector.

The operation of the improved humidifying unit should be readily apparent from the foregoing detailed description of the structure, and when the heaters 11 are in operation, the air circulates rapidly thru the flue formed by the passage 10. As the air flows past the heaters 11, it is thoroughly heated and is subsequently projected by the curved upper end of the partition 9, thru the liquid soaked screen 25 spanning the outlet 12, thus absorbing the moisture and producing rapid humidification. If it is desired to vary the quantity of liquid deposited upon the screen 25, without affecting the degree of heating, the valve 27 may be adjusted to cause more or less liquid to flow from the tank 23, and fresh liquid can readily be supplied to this tank by removing the filling plug 26. If it is desired to cut out one of the heaters 11, this may readily be done by merely adjusting the switch 21 in an obvious manner, thus permitting both the degree of heating and the quantity of moisture to be varied either simultaneously or independently if desired. Any excess liquid delivered from the lower end of the screen 25 will accumulate in the reservoir 24 and may be drawn off thru the drain 32, and the tank 23 may likewise be drained thru the drain pipe 33.

It will also be observed that the casing 8 provides an effective article of furniture, and the humidifying mechanism may be conveniently removed from the casing 8 merely by opening the cover 14. The heaters 11 are insertable and removable thru the opening 20 in one of the side frames 17, and practically the entire structure 6 may be formed of sheet metal and of standard piping and other equipment. The structure, besides being compact, may be readily moved from place to place as desired, and does not embody any moving parts such as motors and fans which tend to create undesirable noises.

While the humidifying structure has been illustrated as being applied to a portable unit, it will be apparent that this structure may also be applied to permanent piping, such as a hot air heating system. The formation of the liquid distributing structure is of importance in securing uniform and rapid humidification, and this structure has been found to operate in a very satisfactory manner in actual commercial use. The 7

wicks 29 insure uniformity of distribution of the liquid over the screen 25, and the porous wicks 31 tend to prevent undesirably rapid flow of the liquid along the louver screen 25. The entire structure is obviously simple and can be manufactured and sold at minimum cost.

It should be understood that it is not desired to limit the invention to the exact details of construction and to the precise mode of operation herein shown and described, for various modifications within the scope of the claims may occur to persons skilled in the art.

It is claimed and desired to secure by Letters Patent:

15 1. In combination, means forming a gas passage, a series of porous troughs extending across said passage, a liquid header having a series of openings disposed above an upper one of said troughs, wicks in said openings for conducting liquid thru said openings to said upper trough, and means for conducting excess liquid from the upper trough to the troughs below.

25 2. In combination, means forming a substantially vertical gas passage having a laterally directed upper outlet, a series of superimposed porous troughs spanning said outlet and each comprising a screen and a porous lining therefor, a liquid header having a series of openings disposed above the upper of said troughs, and means 30 operating by capillary attraction to conduct liquid from said openings to said upper trough.

35 3. In combination, a casing forming a substantially vertical gas passage having a laterally directed upper outlet, means for heating gas flowing through said passage in advance of said outlet, a series of superimposed porous troughs spanning said outlet, said troughs comprising metal screen lined with porous material and being disposed so as to cause the air flowing through said 40 outlet to travel over said porous material, and means for effecting uniform distribution and delivery of liquid into the upper of said troughs throughout its entire length.

45 4. In combination, a casing forming an upwardly directed gas passage having a laterally directed upper outlet, a series of superimposed troughs completely spanning said outlet, each of said troughs comprising an elongated substantially horizontal downwardly concave screen having therein a porous lining and the successive troughs being disposed closely adjacent to each other, and means for delivering liquid in regulated quantities into the upper of said troughs throughout its entire length.

50 5. In combination, a casing forming an upwardly directed gas passage having a laterally directed upper outlet, a series of closely adjacent superimposed troughs spanning said outlet, each of said troughs comprising an elongated screen of 55 V-shaped transverse cross-section and a porous lining removably confined therein, and means for delivering liquid to the lining of said upper trough throughout the entire length thereof.

60 6. In combination, a casing forming an upwardly directed gas passage having a laterally di-

rected upper outlet, a series of closely adjacent superimposed troughs spanning said outlet, each of said troughs comprising an elongated screen of V-shaped transverse cross-section and a porous lining removably confined therein, means for delivering liquid to the lining of said upper trough throughout the entire length thereof, and heating means disposed within said passage in advance of said outlet, said heating means being removable without removing said troughs from said casing.

7. In combination, a casing having therein an upwardly directed gas passage provided with a laterally directed upper outlet, a series of superimposed troughs spanning said outlet, each of said troughs comprising an elongated substantially horizontal V-shaped screen and a porous lining confined within said screen, a liquid header disposed above the upper of said troughs and having a series of openings disposed along said trough, and wick means for conducting liquid from said openings to the lining of said upper trough.

8. In combination, a casing having therein an upwardly directed gas passage provided with a laterally directed upper outlet, a series of superimposed troughs spanning said outlet, each of said troughs comprising an elongated substantially horizontal V-shaped screen and a porous lining confined within said screen, a liquid reservoir carried by said casing above said passage, a liquid header communicating with said reservoir and having a series of openings disposed along the upper of said troughs, and means operating by capillary attraction to conduct liquid from said openings to the lining of said upper trough.

9. In combination, a portable casing forming an upwardly directed gas passage provided with a laterally directed upper outlet in a side wall of said casing, a series of superimposed porous troughs carried by said casing and spanning said outlet and each comprising a screen and a porous lining therefor, a liquid reservoir confined within said casing above said passage, a liquid header communicating with said reservoir and having a series of openings disposed along and above the upper of said troughs, and means for conducting liquid from said openings to the upper of said troughs.

10. In combination, a portable casing forming an upwardly directed gas passage provided with a laterally directed upper outlet in a side wall of said casing, a series of superimposed porous troughs carried by said casing and spanning said outlet and each comprising a screen and a porous lining therefor, a liquid reservoir confined within said casing above said passage, a liquid header communicating with said reservoir and having a series of openings disposed along and above the upper of said troughs, means for conducting liquid from said openings to the upper of said troughs, and means within said casing below the lower of said troughs for collecting excess liquid dropping from said troughs.
